BODY BRACE

Anton W. Bauman, Hamilton, Ohio

Application November 22, 1930
Serial No. 497,547

4 Claims. (Cl. 128—80)

This invention relates to body braces and particularly to braces for use in cases of children who have been afflicted with infantile paralysis.

In the treatment of persons who have been afflicted with infantile paralysis, it is necessary to hold the members on the afflicted side, in proper relation to each other and to assist as much as possible their functioning until they have again become strong.

10 The primary object of my invention is the provision of an improved body brace.

Another object of the invention is the provision of an improved body brace which will extend from the armpit to the bottom of the foot and hold the parts in proper relation.

15 Another and still further object of my invention is the provision of an improved brace having a positive holding means on three sides of the upper portion of the lower leg to hold the leg in proper relation to the upper leg.

20 Another and still further object of the invention is the provision of such a brace extending from the armpit to the foot and also holding the upper arm in proper relation.

25 Another and still further object of the invention is the provision of such a brace which will not only hold the leg members in proper relation but will hold the parts of the knee and ankle in their proper respective places.

30 Other and further objects of the invention will be apparent to one skilled in the art from a reading of the complete specification and claims.

Referring to the drawing wherein I have illustrated an embodiment of my invention,

35 Figure 1 is a side view of my invention with the knee and hip joints bent to illustrate its conformity to body movements.

Figure 2 is a front view of the invention with the ankle and knee pads in place, the parts being upright.

40 Figure 3 is a detail view of the brace member 18 at the top of the lower leg member.

Throughout the drawing, the same reference characters refer to the same or similar parts.

45 The numeral 10 designates a foot-engaging member which is securely attached to the lower brace section 11. A securing member, preferably a strap 12 having two buckles, is attached to the lower brace section 11 at a point just below the

50 ankle. At the upper end of the lower section 11 is a pivot 13 which pivots the lower member 11 to the lower leg section 14. A screw 15 is secured to the lower section 11 through the slot 16 which is located at the lower end of the lower leg member 14.

Just above the lower end of the lower leg member 14 is a strap member 17^a similar in construction to the strap member 12 already described. An ankle pad 17 is provided with four strap ends 17', the two upper of which are for cooperation with the buckles of the strap member 17^a and the two lower ones for cooperation with the buckles of the strap member 12. I also provide a strap 17^b attached to the lower leg member 14 and of sufficient length to go around the leg of the patient and be secured by its own buckle. A strap member 17^c having two buckles is secured at a point below the knee point which is the upper end of the lower leg member 14.

55 At a point immediately below the knee point, I have placed a brace member 18 which passes behind the leg and is provided with a slot and screw adjustment 18^a. By means of this adjustment, this brace member may be made to fit legs of various widths.

60 An upper leg member 19 is pivoted to the lower leg member 14 as at 20. Straps 20^a, 20^b are provided for securing the upper leg member to the upper leg of the patient and except for being longer are in construction similar to the strap 17^b already described.

65 A strap 20^c, having two buckles, and similar in construction to the strap member 17^c, is provided just above the pivot 20.

70 A knee pad 21 having four extending straps 21', is provided for cooperation with the straps 17^c and 20^c. This knee pad 21 holds the knee close to the knee joint of the brace and acts with relation to the knee, in a manner similar to the action of the pad 17 in holding the bones of the ankle in proper relative position.

75 At the upper end of the upper leg member 19 is a pivot 22 which pivots the leg member 19 to a body member composed of two relatively adjustable members 23^a and 23^b.

80 These relatively adjustable members 23^a, 23^b are held in place by two screws 23^c which operate in a suitable slot 23^d in the member 23^b.

85 At the top of the member 23^b is an armpit engaging member 24 which is preferably made of a material which is more or less resilient.

90 Secured to the lower body member 23^a, is a resilient arm-encircling member 25 and secured to the upper body member 23^b, is a similarly constructed, but longer arm-encircling member 26. These arm-encircling members are preferably made of elastic and are provided respectively

110

with laced ends to facilitate application and removal from the patient.

To assist the patient in proper knee movement, I provide a means for normally maintaining the upper leg member 19 and the lower leg member 14 in axial alignment. Extending to the rear of the lower leg member 14 and adjacent its upper end is a spring holding member 27. On a short extension of the lower end of

the upper leg member 19 is a small hole 28 to which is attached one end of the spring 29. The other end of this spring 29 is attached to the rear end of the spring holding member 27. It will be noted that the parts are so constructed that the spring will always tend to bring the upper and lower leg members 19, 14 into axial alignment. This assists the knee of the wearer to properly function. It will also be noted that the working parts of the spring device are all to the rear of the leg members 19, 14 when these members are in axial alignment.

To stop the relative movement of the parts 19 and 14 at the proper point, a screw 30 is provided. To permit of adjustment of this stop, a plurality of holes 30', in which this screw may be inserted, are provided. Similarly, the screw 31 and a plurality of holes 31' are provided to give an adjustable stop means at the joint between the upper end of the leg member 19 and the lower end of the body member 23a.

In using my invention, the brace is so adjusted as to hold all of the parts in snug position on the leg and at the joints. The adjustment 23c is so adjusted that when the parts are in elongated position as shown in Figure 2, there will be sufficient pressure at the armpit to take a portion of the weight of the body. In applying the brace to the patient, the position of the limiting screws 30 and 31 should be carefully noted and adjustments made to accord with the relative positions of the limbs which the doctor in charge of the patient desires to obtain.

While I have shown and described in detail an embodiment of my invention, I desire to have it understood that I do not limit myself to the exact showing and that modifications and changes may be made without departing from the spirit of the invention and within the scope of the invention as claimed.

Having described my invention what I claim and desire to secure by Letters Patent is:—

1. A body brace comprising a foot engaging member, a single lower leg member pivoted thereto, means for limiting the movement of the foot member relatively to the lower leg member, an upper leg member pivoted to the lower leg member, resilient means for normally holding the upper and lower leg members in substantially coaxial position and so placed as to be substantially in the rear of the forward edge of the leg members when in substantially coaxial positions, variable stop means for adjusting the limit of movement between the upper and lower leg members, a stiff brace member

65

for engaging the sides and rear of the leg adjacent the knee and secured to the lower leg member, a body member for extending to the armpit and pivoted to the upper leg member, this body member being provided with an armpit engaging member and resilient arm-encircling means attached to the body member for holding the arm of the patient close to the body member.

80

2. A body brace comprising a foot engaging member, a single lower leg member pivoted thereto at the ankle position, an ankle pad opposite the pivot point to hold the ankle in position, strap means for holding the ankle pad in place and secured to the foot and lower leg members, an upper leg member pivoted to the lower leg member at the knee position, a knee pad opposite the pivot point between the lower and upper leg members and having strap means for securing the same to each, means for normally holding the upper and lower leg members in substantially coaxial position and so placed as to be substantially in the rear of the forward edge of the leg members when in substantially coaxial positions, a body member for extending to the armpit and adjustable as to length and pivoted to the upper leg member and resilient means attached to the body member for surrounding the patient's arm to hold the same in position.

95

3. A body brace comprising a foot engaging member, a single lower leg member pivoted thereto, means for limiting the movement of the foot member relatively to the lower leg member, an upper leg member pivoted to the lower leg member, the upper leg member having an extension at its lower end in prolongation of its axis, the lower leg member having at its upper end a rearwardly extending arm, resilient means for connecting the extension and arm together, thereby normally holding the upper and lower leg members in substantially coaxial position, variable stop means for adjusting the limit of movement between the upper and lower leg members and a body member for extending to the armpit and pivoted to the upper leg member and being provided with an armpit engaging member.

105

4. A body brace comprising a foot engaging member, a single lower leg member pivoted thereto, means for limiting the movement of the foot member relatively to the lower leg member, an upper leg member pivoted to the lower leg member, resilient means for normally holding the upper and lower leg members in substantially coaxial position, a body member for extending to the armpit and pivoted to the upper leg member, this body member being provided with an armpit engaging member, and resilient arm-encircling means attached to the body members for holding the arm of the patient close to the body member.
